UNITED STATES PATENT OFFICE

ANTHONY CAMINETTI, JR., OF SAN FRANCISCO, CALIFORNIA, ASSIGNOR, BY MESNE ASSIGNMENTS, TO CHARLES N. NEWMAN, OF STOCKTON, CALIFORNIA

SPOTLIGHT

Application filed November 2, 1926. Serial No. 145,826.

My invention relates to new and useful improvements in spotlights and more particularly to a mounting for the operating rod of a spotlight similar to that disclosed in my copending application filed October 6, 1925, Serial No. 60,857 in which the light is adapted to be swung horizontally or vertically by means of a single operating or control rod.

10 The principal object of the invention resides in the provision of a mounting for the operating rod in which the rod may be both slidably and rotatably supported.

Another object of the invention consists in 15 forming the mounting in such a manner that the operating rod may be made up of a plurality of sections which may be adjusted at various angles one with respect to the other.

20 With the above and other objects in view, which will appear as the description proceeds, my invention consists in the novel details of construction and arrangement of parts described in the following specifica-

25 tion and illustrated in the accompanying drawings, and while I have illustrated and described the preferred embodiments of the invention, as they now appear to me, it will be understood that such changes may be 30 made as will fall within the scope of the appended claims.

In the drawings:

Fig. 1 is a side elevation.

35 Figs. 2 and 3 are details of the forward bearing, and

Figs. 4 and 5 are details of one of the rear bearings.

In the drawings 1 indicates the chassis, of 40 an automobile, supported by the wheels 2, 3 indicates the engine of ordinary or well-known construction, 4 the water jacket, 5 the dash, and 6 the instrument board. The spotlight shown at 7 is secured to the thimble 8 around the filling opening of the water jacket by means of the clamps 9.

The light is mounted for both horizontal and vertical swinging movement as disclosed in my copending application above identified and is operated through means of a rod which 50 extends from the light to a position within

reach of the operator of the vehicle. The operating rod is formed of a plurality of sections and the sections are connected by means of universal joints whereby they may be angularly adjusted one with respect to 55 the other. At 10 I have shown a relatively short section of rod connected at one end to the light and at its opposite end is connected by means of the universal joint 11 to the rod section 12. The section 10 is preferably ar- 60 ranged horizontally in front of the water jacket or radiator and the section 12 extends through the space between the top of the water jacket and the radiator and preferably is positioned as near horizontally as possible. Secured to the radiator shell flange 13 by 65 means of the screws 14 or other suitable fastenings is the plate 15 having a socket formed adjacent its upper end and supporting the ball 16 having a passage therein and through which the rod section 12 extends. The plate 15 has the ears 17 formed on its side edges and through which the fastenings 14 are passed.

70 Secured to the dash 5 by means of the bolts 18 or other suitable fastenings is a plate 19 formed with a socket to receive the ball 20 having a passage therethrough. Secured to the instrument board 6 by means of the bolts 21 or other suitable fastenings is a plate 22 75 having a socket formed therein for the reception of the ball 23 which has a passage therethrough. A rod section 24 extends through the passages in the balls 20 and 23. Secured to the outer end of this rod section 80 85 24 is a handhold 25 within easy reach of the operator of the vehicle. A rod section 26 is connected to the inner end of the section 24 by means of the universal joint 27 and at the opposite end is connected to the rod section 12 by means of the universal joint 28.

90 From the above detail description it will be noted that I have provided a novel form of mounting for the sections of the operating rod of the spotlight. The rod sections are supported or mounted in the ball and socket bearings so that one section may be arranged at an angle relative to the other and at the same time the sections are mounted for either 95 100 slidable or rotatable movement for swinging

the spotlight either in a horizontal or a vertical direction as may be desired. It can be appreciated that in various types or makes of automobiles that the rod sections will have to be mounted in slightly different positions or at various angles to get around the operating mechanism of the engine, etc. In the drawings the rod section 12 is shown arranged at a slight angle and the ball 16 may be adjusted in the socket of the plate 15 to accommodate for this angle. The bearings or mountings shown connected to the dash and to the instrument board may be either in a direct longitudinal line or at an angle one with respect to the other so that the rod section 24 may either extend perfectly straight or at an angle. It will also be appreciated that when the sections are slid longitudinally in the bearings that they will assume slightly different angles and the ball and socket bearings accommodate these different angles.

Having fully described my invention what I claim as new and desire to secure by Letters Patent is:

In combination with a dirigible automobile lamp adapted to be adjusted in a horizontal and also in a vertical plane, actuating means therefor including a rod comprising end sections and an intermediate section, one end section being connected to the lamp and the other end section provided with hand operable means remote from the lamp, a universal joint connecting each of said end sections with the intermediate section, and longitudinally spaced ball and socket joints supporting the end sections of the rod for rotatable and slideable movement, the ball and socket joints being spaced from the universal joints to allow for the sliding movement of the end sections of the rod in either direction with the intermediate section, each of said ball and socket joints including a socket and a ball frictionally held therein but adapted for universal movement and each of the balls having an axial hole therein through which the rod section passes.

In testimony whereof I hereunto affix my signature.

50 ANTHONY CAMINETTI, JR.
